WINDOW FRAME AND SASH

Michael Garros, Garwood, N. J., assignor of fifty
per cent to Edgar F. Widin, Garwood, N. J.

Application August 24, 1945, Serial No. 612,354

1 Claim. (Cl. 20—43)

1

This invention relates to a window frame and sash.

An object of the invention is the construction of novel means whereby window sashes can be adjusted in a vertical plane within the window frame, but when desired, the sashes can be swung outwardly into the room or building, as the operator desires.

Another object of the invention is the construction of vertically movable sashes, which are normally retained from swinging or pivoting action, but when the operator desires, he can release the upper end of a sash, or sashes, to permit the sash to be swung inwardly, for inspection or repair, or for cleaning, as the case may be.

A still further object of the invention is the construction of sashes with efficient and novel means whereby they are attached to the cables or chains, or other suspending means, that usually have weights attached thereto, the weights and suspending means being of any common type.

With the foregoing and other objects in view, my invention comprises certain novel constructions, combinations and arrangements of parts as will be hereinafter fully described, illustrated in the accompanying drawings, and more particularly pointed out in the appended claim.

In the drawings:

Figure 1 is a view partly in front elevation and partly in section of a window frame and sashes constructed in accordance with the present invention.

Figure 2 is a vertical sectional view taken on line 2—2, Fig. 1 and looking in the direction of the arrows.

Figure 3 is a vertical central sectional view of the window frame, showing the sashes in position ready to be swung outwardly, while

Figure 4 is a similar view, with the sashes swung outwardly.

Figure 5 is a fragmentary view of the window frame and the upper sash, showing partly in section and partly in elevation the means for suspending the sash on the suspension means.

Figure 6 is a fragmentary sectional view of the frame and the lower sash, showing the means whereby the sash is attached to the suspension means.

Figure 7 is a fragmentary view of the apparatus, showing the position of the sash lock on the sash.

Figure 8 is a vertical sectional view taken on line 8—8, Fig. 7, and looking in the direction of the arrows.

Figure 9 is a horizontal sectional view taken on

2

line 9—9, Fig. 7, and looking in the direction of the arrows.

Referring to the drawings, in which the preferred embodiment of the invention is shown, 1 designates any type of a window frame, which is provided with registering rear grooves 2 and front grooves 3. Slidably mounted in these grooves is a lower sash 4 and an upper sash 5.

On the lower sash 4 is a pair of bracket devices 6. Each bracket device 6 (Fig. 6) comprises a flat plate 7, which is screwed to the bottom edge of the sash 4. This flat plate 7 is provided at its outer end with a hollow hub 8. A pin 9 extends into hub 8, with a cotter pin 10 extending through the hub 8 and pin 9, holding the pin in position upon the bracket plate 7. Pin 9 is provided on its outer end with head 11. The cable 12, which may be a chain (not shown), is attached in any suitable manner to pin 9 between head 11 and the outer end of hub 8. The advantage of having the pin 9 detachable resides in the making of the operation of attaching the cable 12 much easier than would otherwise be the case. The cable (or chain) is run over the ordinary pulley 13 which is carried by the frame 1, and a suitable weight (not shown) is attached to the cable or lifting means.

On the lower end or edge of the upper sash 5 are two bracket devices 14, Fig. 5. Each of these bracket devices 14 comprises an L-shaped plate 15, which is screwed to the sash. A hollow hub 16 extends through the plate 15 and is fixedly mounted thereon. A pin 9 extends through hub 16, the pin being provided on its outer end with head 17. Before fastening the plate 15 in position, a cotter pin 18 is extended through the hub 16, as well as pin 9. The inner end of hub 16 and pin 18 is in a socket 19 of the sash 5. The lifting cable 12a, which may be a chain (not shown) is attached to pin 9a between head 17 and hub 16. By this novel structure the attaching of the lifting means 12a is easily accomplished.

The hubs 16 and pins 9a of the two bracket devices 14 travel in the two rear grooves 2 and at all times are retained in these grooves, acting as the pivot for the sash.

The hubs 8 and pins 9 of bracket devices 6, that are attached to the lower end of sash 4 travel or are slidably mounted in the pair of front grooves 3, acting as the pivot for the lower sash 4 when it is desired to swing the sash outwardly into the room or dwelling, as clearly shown in Figure 4.

On the upper portion of each sash are two sash locks 20, Fig. 9. Each sash lock 20 comprises a

casing 21, in which is mounted a spring pressed bolt 22, the outer end of which bolt normally extends into a groove of the window frame 1. A ring 23 is pivotally attached to bolt 22 for enabling the operator to withdraw the bolt 22 from the groove of the window frame or from the lock plate 24. The specific details of the sash lock 20 are fully disclosed in my co-pending application, entitled "Sash lock." The lock plate 24 is provided with a beveled notch 25 (Fig. 8) to facilitate the movement of the outer end of bolt 22 into the aperture 26 of plate 24, whereupon the sash is retained against sliding movement upon the window frame. It is to be noted that the ring 23 normally rests in the cup 27 of the casing 21, but by the operator grasping the ring and pulling outwardly, the bolt 22 can be easily operated, to release the sash lock.

The window frame 1 has portion 28 lower than portion 29 for the purpose hereinafter described. A pair of very narrow rear cleats 30 is on the window frame 1 and a pair of very narrow front cleats 31 is also on the window frame. The lower end 32 of the rear cleats 30 terminate short of the bottom portion 28 for the purpose hereinafter described. The upper ends of the front cleats 31, at 33, terminate short of the middle of the window frame (Figs. 1 and 2) for the purpose hereinafter described.

When the two window sashes 4 and 5 are in a closed position within the frame, as shown in Figure 1, the sash locks 20 are in engagement with the plates 24, thereby locking the sashes in a non-sliding condition. By the operator grasping the rings 23 of the sash locks on either sash, he can release the locks, permitting the sash to be slid up and down within the window frame.

When it is desired to swing the sashes out into the room, the operation is as follows: the upper sash 5 is slid down into the bottom portion of the window frame, as shown in Figure 3. In this position the upper sash 5 has its upper end slightly below the bottom end of the lower sash 4, which is now in upper part of the window frame, as shown in Figure 3. Then the operator grasps the rings 23 of the sash locks on upper sash 5, pulling on the sliding bolts to release the sash locks from engagement with the units of the window frame, while at the same time pulling outwardly on the rings, causing the window sash 5 to pivot on the bracket devices 14, swinging outwardly between front cleats 31, which results in the window sash having its rear portion engaging the cut-off or lower ends 32 of the rear cleats 30. When it is desired to swing the lower sash 4 outwardly, the sash locks are released in the same manner as just described and the upper end of the lower sash is swung out into the room, as

shown in Figures 3 and 4. When placing either of the sashes back in their normal position within the frame, all that is necessary is to grasp the rings 23 of the sash lock, holding the outer ends of the sliding bolts clear of the window frame, until the sash is in its vertical position within the frame. Then, upon releasing the rings 23, the sliding bolts will normally move into their set position, with their outer ends in the grooves of the frame. Consequently, on each sash there are two guiding means, to wit: the bolts 22 and the hubs 8 and 16 of the bracket devices. These bracket devices are an important and essential structure of my improved apparatus.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claim.

What I claim is:

In an apparatus of the class described, the combination of a window frame provided with rear cleats, and with front cleats, said window frame having at its bottom a rear portion lower than the front portion of the bottom, said rear cleats terminating short of the lower portion of the bottom of the window frame, said front cleats terminating at their upper ends at approximately the middle of the window frame, an upper sash slidably mounted within the window frame and adapted to engage the lower portion at the bottom of the window frame and be pivoted outwardly to rest against the lower ends of the rear cleats, a lower sash slidably mounted in said window frame and adapted to be swung outwardly to rest upon the upper ends of said front cleats, and each sash being provided with lock devices cooperating with the window frame, whereby the sash is held normally against pivotal movement upon the window frame.

MICHAEL GARROS.
